CLAIM

The ornamental design for a pair of side rocker panels for an automobile as shown and described.

DESCRIPTION

FIG. 1 is a front right top isometric view of a pair of side rocker panels for an automobile showing my new design; FIG. 2 is a rear left bottom isometric view thereof; FIG. 3 is a front elevation view thereof; FIG. 4 is a back elevation view thereof; FIG. 5 is a right side elevation view thereof; FIG. 6 is a left side elevation view thereof; FIG. 7 is a top plan view thereof; and FIG. 8 is a bottom plan view thereof.

FIG. 9 is a front right top isometric view of a pair of side rocker panels for an automobile showing my new design; FIG. 10 is a rear left bottom isometric view thereof; FIG. 11 is a front elevation view thereof; FIG. 12 is a back elevation view thereof; FIG. 13 is a right side elevation view thereof; FIG. 14 is a left side elevation view thereof; FIG. 15 is a top plan view thereof; and, FIG. 16 is a bottom plan view thereof.

The features shown in broken lines in the drawing depict portions of the design that form no part of the claimed design.

1 Claim, 16 Drawing Sheets
